UNITED STATES PATENT OFFICE

100,667

DESIGN FOR A LAMP SHADE

Harry M. Laxer, New York, N. Y.

Application June 24, 1936, Serial No. 63,460

Term of patent 3½ years

To all whom it may concern:

Be it known that I, Harry M. Laxer, a citizen of the United States and a resident of the city, county, and State of New York, in the Borough of Manhattan, city and State of New York, have invented a new, original, and ornamental Design for Lamp Shades, of which the following is a specification, reference being had to the accompanying drawing, forming part thereof.

Figure 1 is a planar development of a lamp

shade with the frame and supports omitted, showing my new design; and

Figure 2 is a front elevation of the assembled lamp shade showing a portion of the decoration shown in Figure 1.

I claim:

The ornamental design for a lamp shade, as shown and described.

HARRY M. LAXER.
